DATA PRINTER

James J. Belcher, Canoga Park, Calif., assignor to Clary Corporation, San Gabriel, Calif., a corporation of California

Filed July 31, 1969, Ser. No. 18,490

Term of patent 14 years

Int. Cl. D18—03

U.S. Cl. D64—11

FIG. 1

FIG. 2

FIG. 3

FIG. 4

FIG. 5

FIG. 1 is a front perspective view of a data printer showing my new design;

FIG. 2 is a front elevational view thereof;

FIG. 3 is a top plan view thereof;

FIG. 4 is an elevational view taken from the right side thereof; and

FIG. 5 is a fragmentary cross sectional view taken on line 5-5 of FIG. 3.

I claim:

The ornamental design for a data printer, substantially as shown.
